UNITED STATES PATENT OFFICE

WILLIAM H. CANNARD, OF GREEN BAY, WISCONSIN

INTERFOLDING MACHINE

Application filed August 1, 1928. Serial No. 296,677.

This invention relates to improvements in interlocking machines and, more particularly, to machines for interlocking and packaging sheets of paper and the like.

5 The principal object of the invention is to provide an interlocking machine of the type specified with mechanism operating in a novel way to rapidly and accurately fold sheets fed to the machine.

10 Another object of the invention is to provide an interlocking machine having tuckers with a pair of packers for each tucker and cooperating therewith to produce a pair of folds for each cycle of operation.

15 A further object is to provide a machine of the type specified with upper and lower tuckers each having a pair of packers with which it cooperates to fold the sheets in opposite directions, the tucker being brought 20 into cooperative relation with its packers alternately, thus producing two folded and interlocked sheets for each cycle of operation.

Still another object is to provide an interlocking machine with novel feed means for 25 feeding sheets continuously to the interlocking mechanism, the feed means being arranged to speed up delivery of the sheets to insure proper overlapping of successive sheets.

30 Other objects and advantages of the invention will in part be obvious and in part more fully brought out as the description proceeds.

In the accompanying drawings, I have illustrated a practical embodiment of my invention; but it is to be understood that the drawings are illustrative, merely, and are not to be construed as limiting the invention to the specific structural elements therein disclosed. It is obvious that many modifications may be made by those skilled in the art without departing from the spirit and scope of the invention and without sacrificing any of its salient features and advantages.

45 In these drawings:

Fig. 1 is a side elevation, partly in section and partly diagrammatic, showing the interlocking mechanism of my invention;

50 Fig. 2 is a side elevation, more or less diagrammatic, showing particularly the action

of the packers, there being shown but one of each of the pairs of packers for the sake of clearness; and

Fig. 3 is a side elevation from the opposite end of the machine and shows particularly the driving mechanism for all the operating parts.

In the drawings, I have illustrated only such parts of the machine as are essential to a complete understanding of my invention.

The reference-numeral 1 indicates the main drive-shaft of the machine from which all of the operating parts receive their motion. This shaft drives directly a gear 2 on a bed-roll 3 over which travels the paper or other material to be folded, the paper being guided over the bed-roll by means of guide-rolls 4 and 5. Paper is supplied to the machine in the form of a continuous web from a large roll suitably supported at the rear of the machine, as in common practice.

Immediately above the bed-roll 3 is mounted a cutter-roll 6 driven by a gear 7 which meshes with the gear 2 on the bed-roll. The cutter-roll is provided with a cutter-blade 75 which enters a groove in the bed-roll in the usual manner. By this means, the web of paper is severed into sheets and the leading end of the sheet is carried by pins on the bed-roll to the feed mechanism now to be described.

The feed mechanism includes feed-rolls 8, 9 and 10 and a plurality of belts 11 which carry the sheets forward and downward between strippers 12 and 13. The upper feed-rolls 8 are driven directly by the bed-roll through a gear 14 which meshes with the gear 2, while the lower feed-rolls 9 and 10 are driven from the bed-roll through intermediate gearing 15 and 16. The shafts supporting the feed-rolls 9 and 10 are provided with intermeshing gears 17 by which they are rotated in unison and which also serve to drive the shaft of one of the sets of packers, as hereinafter more fully described.

The gearing 15, 16, is so constructed and arranged that the lower feed-rolls will be driven at a predetermined greater speed than the upper rolls so that the sheet will gain one-third its length. This is an important fea-

ture of my invention and insures that the sheets will overlap the proper amount for the interfolding action presently to be described.

The folding mechanism includes an upper tucker 18 having a tucker-blade 19 and a lower tucker 20 having a tucker-blade 21. The tucker 18 is pivoted intermediate its ends at 22 and is provided with a cam-roller 23 which rides on the periphery of a cam 24 mounted on a cam-shaft 25. The tucker 20 is pivoted at 26 and is provided with a cam-roller 27 which rides on the periphery of a cam 28 also mounted on the cam-shaft 25. The cam-shaft 5 has direct driving connection with the main shaft 1 through a gear 29. From the drawings, it will be clear that the cams 24 and 28 are so arranged that upon rotation of the cam-shaft 25 the tuckers 18 and 20 will be alternately depressed and elevated, thus forming, in conjunction with the packers now to be described, alternate folds at the upper and lower edges of the sheets.

In order to carrying out the principal object of my invention, which is to speed up production and at the same time insure accuracy of folding, I have provided the machine with a pair of packers for each of the tuckers. Thus, the tucker 18 cooperates with the upper packers 30 and 31 and the tucker 20 with the lower packers 32 and 33. The packers 30 and 31 are eccentrically mounted on a shaft 34 and are provided near their lower ends with ears or lugs 35 and 36 which are pivoted on a shaft 37. The packers 32 and 33 are eccentrically mounted on a shaft 38 and are provided near their upper ends with ears or lugs 39 and 40 which are pivoted on a shaft 41. The shaft 34 which actuates the upper packers is provided with a gear 42 which receives its motion from the gears 17 heretofore described. Thus, the upper packers are actuated in properly timed relation to their cooperating tucker 18. The shaft 38 is provided with a sprocket-wheel 43 which is rotated by a sprocket chain 44 operated by a sprocket-wheel 45 on the main drive-shaft 1. Thus, the lower packers are actuated in properly timed relation to their cooperating tucker 20.

From an inspection of Fig. 1, it will be clear that the pairs of packers are so mounted upon their respective shafts that they will alternately assume a position wherein they cooperate with their respective tucker-blade to form the tuck and then move to a position where they crease the tucked portion and press the folded sheet against the stack of previously folded sheets. Thus, in Fig. 1, the lower packer 32 is in position to receive the tucker-blade 21 to form a fold at the lower edge of the sheet and at the same time the upper packer 30 is pressing the sheet which has just been folded at the upper edge against the stack of previously folded sheets. The other upper packer 31 is shown

moving out into position to receive the tucker blade 19 for making the succeeding fold at the upper edge. It will thus be seen that for each revolution of the shafts 34 and 38 two folds will be produced at each edge of the sheets and, therefore, two sheets will be completely folded and inter-folded for each cycle of operation.

In Fig. 2 I have illustrated somewhat diagrammatically the movement of the packers. The dotted lines Y indicate the evolution of the eccentrics in the course of the rotation of the shafts 34 and 38, while the dotted lines X indicate the path of travel of the packers, this path being elliptical. In this figure, the packers 30 and 32 are in the same position as that illustrated in Fig. 1. The upper packer 30 is shown pressing a newly folded sheet against the stack of previously folded sheets. From that position its movement is upward and outward following the arrows until it reaches the position where it again will receive the tucker-blade 19 to form another fold. The lower packer 32 is shown in position to receive the tucker-blade 21 after which it will follow the arrows in an upward and forward movement until it presses the sheet which has just been tucked against the stack. The elliptical movement of the packers is an important feature of my invention and insures that each of the packers will at the proper time be in position to receive its cooperating tucker-blade and after the fold has been made, continued movement of the packers will crease the sheet at the fold line and will also press it against the previously folded sheets.

To receive and hold the sheets as they are folded and interfolded, I have provided a lower table-member 46 and an upper supporting member 47. The latter is made of any desired length and determines the size of the package of interfolded sheets. It may be added that when the machine is first started, it is desirable to place a block of wood or other convenient object on the table 46 so that there will be something against which the first sheets may be folded and pressed.

It is believed that the invention has now been fully and clearly brought out and that its many objects and advantages will be apparent to those skilled in the art. While the description and drawings have been made as for a machine having a single folding mechanism, it will be obvious that the machine may be made of sufficient length to provide two or more such mechanisms and that, therefore, two or more packages of interfolded sheets may be produced at the same time.

What I claim is:

1. In a machine for interfolding sheets, folding mechanism including a tucker, a pair of packers cooperating therewith to fold the sheets, and means to operate said tucker and packers to bring the tucker into cooperative

relation with each of said packers alternately.

2. In a machine for interfolding sheets, folding mechanism including a pivotally mounted tucker, a pair of eccentrically mounted packers adapted to cooperate therewith to fold the sheets, means to oscillate said tucker, means to actuate said packers, and mechanism common to said means to operate them in synchronism, whereby the tucker is brought into cooperative relation with said packers alternately.

3. In a machine for interfolding and packaging sheets, folding mechanism including a pair of tuckers, a pair of packers cooperating with each of said tuckers to fold the sheets, means to operate said tuckers and packers alternately to fold the sheets at opposite edges, and means common to each of said tuckers and its respective pair of packers to bring the tucker into cooperative relation with each of the packers alternately.

4. In a machine for interfolding sheets, means for continuously feeding sheets, a pair of tuckers adapted to engage the sheets in opposite directions, a pair of packers cooperating with each of said tuckers to fold the sheets at opposite edges to produce a package of interfolded sheets, and means to operate said tuckers and pairs of packers alternately to bring each of said tuckers into cooperative relation with its packers alternately, to produce a pair of folds at each edge of the package for each cycle of operation.

5. In a machine for interfolding and packaging sheets, means for feeding sheets, and means for folding the same, said folding means including a pair of pivotally mounted tuckers, means for periodically oscillating said tuckers about their respective pivots, a pair of packers cooperating with each of said tuckers, means for operating said packers, and means common to said oscillating means and said packer-operating means for operating them simultaneously and in synchronism to bring each of the tuckers alternately into cooperative relation with each of its respective packers.

6. In a machine for interfolding and packaging sheets, means for feeding sheets and means for folding the same and forming a package thereof, said folding means including a pair of shafts, a pair of packers eccentrically mounted on each of said shafts, pivotally mounted tuckers adapted to cooperate with said packers to fold the sheets, means to rotate said shafts, means to oscillate said tuckers, and mechanism common to said rotating means and said oscillating means for operating them in synchronism.

7. In a machine for interfolding and packaging sheets, means for feeding sheets, means for folding the same and forming a package thereof, and means to receive said package, said folding means including a pair of shafts,

one above and the other below said package-receiving means, a pair of packers eccentrically mounted on each of said shafts, tuckers adapted to cooperate with said pairs of packers to fold the sheets, and means to rotate said shafts to bring said packers alternately into cooperative relation with said tuckers.

8. In a machine for interfolding and packaging sheets, folding mechanism operative to produce a pair of folds at each edge of the package for each cycle of operation, means to feed sheets to the folding mechanism, and means to increase the rate of feed of the sheets, whereby a pair of sheets are folded and interfolded for each cycle of operation.

9. In a machine for interfolding and packaging sheets, folding mechanism operative to produce a pair of folds at each edge of the package for each cycle of operation, means to feed sheets to the folding mechanism, and means including a feed-roll traveling at a predetermined greater speed than said feed means to increase the rate of feed of the sheets to the folding mechanism.

In testimony whereof I affix my signature.
WILLIAM H. CANNARD.
